SLOT-CLOSING MECHANISM FOR COIN-CONTROLLED VENDING-MACHINES.

1,243,511.

Specification of Letters Patent.

Patented Oct. 16, 1917.

Original application filed December 17, 1914, Serial No. 877,647. Divided and this application filed January 24, 1916. Serial No. 73,776.

To all whom it may concern:

Be it known that I, ALBERT D. GROVER, a citizen of the United States, and a resident of New York city, in the county of New York and State of New York, have invented certain new and useful Improvements in Slot-Closing Mechanism for Coin-Controlled Vending-Machines, of which the following is a specification.

10 This application is a division of my pending case, Serial No. 877,647, filed December 17, 1914, for improvements in coin-controlled vending machines, and the claims in this present application are confined to the slot-closing mechanism set forth in said parent case.

The slot-closer of my present invention automatically closes the coin-entrance slot when the coin-controlled ejecting member 20 reaches a predetermined position—which position is reached when the supply of goods in the machine becomes exhausted.

Viewed in another aspect, my invention comprises a combined washer-catcher and slot-closer which prevents the insertion into the coin-entrance slot of washers or rings, and is so controlled by the delivery mechanism as to close or obstruct the coin-entrance slot when the goods are exhausted.

30 A preferred form of construction embodying my invention is shown in the accompanying drawings in which—

Figure 1 shows a front elevation of the machine, with the front wall partly broken away to expose the interior mechanism.

Fig. 2 is a side elevation of Fig. 1 looking toward the left, with the side wall partly broken away for the sake of clearness; and

Fig. 3 is a top plan view, with portions of 40 the top plate broken away to show the parts beneath.

The casing A of the machine may be of any approved construction and is preferably made of two metallic sections—a rear or 45 box-like section 1 and a front-plate section 2 which is hinged to the rear section at 3. Inside of the casing A is a magazine M which is provided with a plurality of shelves 4 hinged to the back plate of the magazine 50 at 5. In the present instance, I have shown two shelves, but it is obvious that the number may be varied. The purpose of the shelves 4 is to support the vendable goods,

each shelf being adapted to support one package. The right hand hinge of each 55 shelf is provided with a curved extension 6 adapted to engage with the vertically slideable bar 7. The extension 6 of the upper shelf 4 engages in the slot 8 of the operating plate or bar 7, while the extension 6 of the 60 lower shelf 4 engages in the slot 9. The slots 8 and 9 of the operating bar 7 are so arranged that the first downward movement of the bar causes tilting of the lower shelf, while the next downward movement of the 65 bar trips the upper shelf. For this purpose the slot 9 is provided with an angular tripping portion 10 and a vertical rest portion 11. The slot 8 is provided with a vertical rest portion 12 and an angular trip portion 70 13. The bar 7 is yieldingly held in its different positions by a spring 14 having a head 15 adapted to engage in the notches 16, 17 and 18 of the bar 7.

Actuation of the operating bar 7 may be 75 accomplished by any suitable coin-controlled mechanism. For the purpose of illustration, I have shown in the accompanying drawings a hand lever 19 which projects through a slot 20 in the right side of the casing and 80 which is operatively connected with the bar 7 through the medium of the deposited coin. As my present invention is independent of any specific mechanism for operating the bar 7, which may broadly be referred to as 85 a suitable actuating member, I have not deemed it necessary to illustrate or describe any particular form of coin-controlled mechanism which connects the hand lever 19 with the bar 7. A suitable form of such 90 coin-controlled connecting mechanism is 95 fully shown and described in my aforesaid co-pending application, Serial No. 877,647, filed December 17, 1914, of which the present case is a division. For the purpose of this 100 case it will be sufficient to state that the coin is inserted through the coin-entrance slot 21 in the top of the casing, whence it passes down the coin-chute 22 into operative position, so that when the lever 19 is 105 tilted down as far as it will go, the bar 7 will be actuated an amount equal to the distance between the notches 16 and 17 or 17 and 18. Figs. 1 and 2 show the actuating bar 7 and the goods-supporting shelves 4 in 110 their normal position. When the hand le-

ver 19 is pulled down, after the deposit of a proper coin, the bar 7 is pulled downward until the head 15 of the spring 14 rests in the notch 17. During this downward movement of the bar 7 the extension 6 of the lower shelf 4 is rocked forwardly by virtue of its engagement with the tripping portion 10 of the slot 9, with the result that the shelf 4 is tripped into a horizontal position and allows 10 the package to fall into the delivery compartment 23, whence it is withdrawn through a delivery opening in the left side of the casing.

The bar 7 and the lower shelf 4 remain in 15 operated position. At the end of the first movement of the bar 7 the crank extension 6 of the lower shelf rests at the bottom of the inactive portion 11 of the slot 9, while the extension 6 of the upper shelf 4 rests at 20 the bottom of the tripping portion 13 of the slot 8. When, therefore, the bar 7 is next operated, the tripping portion 13 of the slot 8 will rock the upper shelf 4 downwardly to discharge the second package of goods. 25 During this second discharge there will be no movement of the previously tripped lower shelf, because the extension 6 thereof rides in the vertical or inactive portion 11 of the slot 9. When the bar 7 is at the end of 30 its second movement, the head 15 of the spring 14 rests in the upper notch 18. The parts remain in this position until they are reset.

I have provided means for automatically 35 closing or obstructing the coin-entrance slot 21 after the last package of goods has been discharged. Across one end of the coin-slot 21 extends the arm 24 of a lever indicated as a whole by L. This lever is pivoted at 25 to a framework or bracket 26 secured to the underside of the top plate of the casing by rivets 27 or otherwise. The lever L is also provided with an extension 28 and an arm 29. A spring 30 bears at 40 one end against a fixed lug 31 carried by the bracket 26, and at its other end against the extension 28, so as normally to force the arm 24 of the lever L across one end of the coin-entrance slot 21. Associated with the 45 pivot lever L is a slideable bar or bolt 32 which is normally held in retracted position by the arm 29 of the spring-pressed lever L. The bolt 32 is guided in its movements between the side wall 33 of the bracket 26 and the aligned studs 31 and 34 carried by the bracket 26. Between the shoulder 35 of the bolt 32 and the shoulder 36 of the arm 29 is a light expansion spring 37 which is weaker than the spring 30. The bolt 32 50 is reduced at its forward end to form a projection 38 which is beveled on the underside. 60

The members L and 32 constitute a washer-catching device which operates as follows: When a proper coin is inserted

into the coin-entrance opening 21, the edge of the coin engages the arm 24 of the lever L and forces said arm out of the way, thus rocking the lever against the tension of spring 30. As soon as the coin has been pushed in a little 70 over half way, the action of the arm 24 is to snap the coin through the coin-entrance slot into the descending coin-chute beneath. Now, when the inserted check is a ring or washer, or any disk with an opening in the 75 center, the lever L is rocked as before. However, as soon as the arm 29 of the lever L is moved away from the bolt 32, the spring 37 tends to project the bolt 32 across the coin-slot, and as soon as the opening in the inserted ring or washer comes into alignment with the bolt 32, the projection 38 thereof snaps into the opening of the ring or washer and thereby positively locks the same against further insertion. As the 85 underside of the extension 38 is beveled, the intercepted ring or washer may be readily withdrawn. In this way I have provided very simple and efficient means for automatically locking a ring or washer against 90 full entrance into the coin-slot 21. The ready insertion of a good coin in the slot 21 is not interfered with by the pressure of the bolt 32 against the face of the coin by the action of spring 37, because that spring is 95 very weak and exerts only a negligible pressure.

The washer-catching device as above described does not in and of itself form part of my present invention, as it forms the subject-matter of my co-pending application, Serial No. 781,072, filed July 25, 1913, where a slightly modified form is shown, but where the invention of my new washer-catching device is claimed broadly.

I make use of the arm 24 of the lever L to automatically close or obstruct the coin-entrance slot 21 when the machine is empty, so as to prevent the deposit of coins until the machine has been replenished. For this 100 purpose, I have devised means whereby the operating bar 7 so controls the lever L that when the bar reaches its final position (which takes place when the last package is ejected), the lever L is locked in its normal position, thereby closing the coin-entrance slot. In the particular embodiment shown in the drawings, the controlling connection between the bar 7 and the lever L consists of a member 39 pivotally mounted 105 on the stud 40 carried by the rear plate of the casing. The member 39 has an inwardly extending arm 40 and a downwardly and outwardly curved extension 41. A spring blade 42, fixed at its lower end to the projection 42 of the member 38 and bearing at its upper end against the underside of the top of the casing, normally holds the member 39 in the position shown in Fig. 1. The arm 40 terminates in close proximity to the 110

arm 24 of the lever L, but during the normal position of the member 39, the arm 40 is below the plane of operation of the arm 24. The operating bar or member 7 is provided with a lateral projection 43 in alignment with the free end of the extension 41 of the member 39. The distance between the projection 43 and the lower end of the extension 41 is such that after the operating bar 7 completes its final movement (which in the present illustration is its second movement), the projection 43 strikes the extension 41 and rocks the arm 40 upwardly into the path of the arm 24 of the lever L, with the result that the arm 24 is locked against movement. Broadly speaking, therefore, the coin-entrance slot is closed or obstructed when the operating member 7 reaches a predetermined position. This position will, of course, vary in machines of different capacity. For instance, if the machine had a capacity of three packages, the distance between the extension 41 of the member 39 and the projection 43 of the operating member 7 would be so gaged that the member 39 would not be rocked into locking position until after the third or last package has been ejected.

Although I have herein described and shown a specific form of machine embodying the invention of my slot-closing mechanism, I would have it understood that I do not intend to be limited to the structure herein set forth, as it is obvious that in its broad aspect my invention may be mechanically carried out in other ways than that shown.

Having thus described my invention what I claim as new and desire to secure by Letters Patent of the United States, is:

1. In a coin-controlled machine, a casing provided with a coin-entrance slot, coin-testing mechanism associated with said slot and adapted to be automatically actuated by an entering washer to lock the same against full entrance into said slot, said mechanism yieldably engaging the edge of a proper coin and allowing the same to pass through said slot, a coin-controlled operating device, and means whereby said washer-catching mechanism is automatically locked against operation to close said coin-entrance slot when said device reaches a positively predetermined position.

2. In a coin-controlled machine, a casing provided with a coin-entrance slot, a spring-pressed member normally projecting across one end of said slot and adapted to be actuated by the edge of an entering disk or coin, mechanism controlled by said member for automatically locking an inserted washer against full entrance into said slot, a coin-controlled operating device, and connections between said member and said device whereby said member is automatically locked

against operation, thereby closing said coin-entrance slot, when said device reaches a positively predetermined position.

3. In a coin-controlled vending machine, a casing provided with a coin-entrance slot 70 and a magazine for holding the vendable articles, mechanism arranged at said slot and adapted to be automatically actuated by an entering washer or ring to lock the same against full entrance into said slot, a coin-controlled device for discharging the articles from said magazine, said device including a movable member arranged to occupy a predetermined position when said magazine is empty, and means whereby said washer-catching mechanism is automatically locked against operation to close said coin-entrance slot when the magazine is empty. 75

4. In a coin-controlled vending machine, a casing provided with a coin-entrance slot, 80 a spring-pressed member normally projecting across one end of said slot and adapted to be moved aside by an entering coin, a magazine within said casing for holding the vendable goods, a coin-controlled operating 90 device for causing discharge of the goods from said magazine, and means controlled by said device for automatically locking said member in slot-closing position when the supply of goods in said magazine is entirely exhausted. 95

5. In a coin-controlled vending machine, a casing provided with a coin-entrance slot, a spring-pressed member normally projecting across one end of said slot and adapted 100 to be moved aside by an entering coin, a magazine within said casing for holding the vendable goods, a coin-controlled device for causing discharge of the goods from said magazine, and a normally inoperative locking mechanism adapted to be engaged by said device and thereby actuated to lock said member in slot-closing position when the supply of goods in said magazine is entirely exhausted. 105

6. In a coin-controlled machine, a casing provided with a coin-entrance slot, a spring-pressed member normally projecting across one end of said slot and adapted to be moved aside by an entering coin, a coin-controlled 110 device adapted to remain in successively operated positions, and means whereby said member is automatically locked in slot-closing position when said device reaches a positively predetermined position. 115

7. In a coin-controlled vending machine, a shallow and substantially rectangular casing having a coin-entrance slot on top, a member mounted in close proximity to said slot and movable in a plane substantially 125 parallel with said top, a vertically slidable coin-controlled bar mounted at one of the walls of said casing and adapted to remain in successively operated positions, and means whereby said member is automatically locked 130

in slot-closing position when said bar reaches a predetermined position.

8. In a coin-controlled vending machine, a casing having a coin-entrance slot, a pair of movable members mounted in proximity to said slot and coöperating to lock an entering washer against full entrance into said slot, while allowing a proper coin to pass through, a coin-controlled operating device, and means whereby one of said members is

automatically locked in slot-closing position when said device reaches a positively predetermined position.

In witness whereof, I hereunto subscribe my name this 10th day of January, 1916. 15

ALBERT D. GROVER.
